[57] CLAIM

The ornamental design for a lens tissue dispensing unit, as shown and described.

DESCRIPTION

FIG. 1 is a front view of the lens tissue dispensing unit showing our new design;

FIG. 2 is a top view thereof;

FIGS. 3 and 4 are opposing left and right side views thereof;

FIG. 5 is a bottom view thereof;

FIG. 6 is a back view thereof;

FIG. 7 is a top, front, and left side perspective view thereof; and,

FIG. 8 is a bottom, front, and left side perspective view thereof, with the broken line disclosure of a mounting means being shown for illustrative purposes only and forming no part of the claimed design.

FIG. 2

FIG. 3

FIG. 4

FIG. 1

FIG. 6

FIG. 7

FIG. 8
